BLAST FURNACE TUYÈRE

Richard C. Butler, Lowellville, Ohio, assignor of
one-third to John M. Hughes and one-third to
Joseph H. Carter, both of Youngstown, Ohio

Application March 24, 1932, Serial No. 600,872

3 Claims. (CL. 122—6.6)

The invention relates to blast furnace tuyères and the like; and more particularly the invention relates to an all-metal preferably one-piece tuyère having cooling passages therein, and provided with a heavy solid metal nose at the portion or portions thereof which ordinarily burn or wear away during use of the tuyère in a blast furnace.

Tuyères are usually made with double truncated conical walls, an outer end wall and an inner nose wall, a provision being made for circulating cooling water between the double walls, and the thickness of each of the double walls and nose wall usually being substantially the same.

Such tuyères are quickly destroyed when used in a blast furnace, because the molten metal in the furnace comes in contact with the tuyère nose and burns or wears through the thin nose wall. The cooling water then discharges into the furnace, causing a rapid temperature reduction and a consequent heat loss in the furnace hearth. A further heat loss occurs when the blast is shut off for replacing a burned-out or worn-out tuyère. These heat losses materially lower the operating efficiency of the furnace.

Another type of tuyère includes an annular water jacket formed by double walls, and an annularly recessed nose filled with refractory material. However, the refractory material acts to insulate rather than conduct the cooling effect of the circulating medium to the inner portions of the nose, with the result that the thin metal nose walls are quickly burned away due to the intense heat in the furnace, and the refractory metal soon disintegrates and sluffs away when the thin metal retaining walls have been burned away.

Accordingly, it is an object of the present invention to provide a blast furnace tuyère and the like having a solid metal nose projecting into the furnace.

It is a further object of the present invention to provide a blast furnace tuyère and the like having that portion of its nose which projects toward the hottest portions of the furnace hearth formed of solid metal.

It is a further object of the present invention to provide a one-piece metal blast furnace tuyère and the like with a nose, a considerable portion of which may be burned off during continued use without burning through to the tuyère cooling passages, to avoid the necessity of frequent shutdown for replacing burned-out tuyères.

It is likewise an object of the present invention to provide a tuyère made of genuine copper so as to prevent the nose from cracking when subjected

to the intense heat of the furnace during operation.

Moreover, it is an object of the present invention to provide a tuyère which supplies a constant amount of air to the furnace even though a material portion of the nose may have burned away.

It is also an object of the present invention to provide a one-piece all metal tuyère construction, which when used in a blast furnace improves the furnace operating efficiency because of the longevity of the tuyère, and of the elimination of heat losses and frequent shut-downs due to tuyère failures and replacements.

And finally, it is an object of the present invention to provide a blast furnace tuyère construction having the aforesaid desired characteristics, which also has an extremely simple design that renders it readily cast from genuine copper.

These and other objects may be obtained by the present improved constructions, a number of embodiments of which are hereinafter described in detail, which may be stated in general terms as including in a one-piece cast-metal blast furnace tuyère and the like, a cooling jacket cavity formed by inner and outer annular preferably conical walls, an outer end wall and an inner nose wall, the nose wall or a portion thereof having a radial thickness greater than twice the thickness of one of the annular walls and preferably having an axial length approximating or greater than its radial thickness, means for introducing and withdrawing cooling medium to and from the jacket cavity, and preferably means projecting from the nose wall into the jacket cavity for increasing the cooling effect of the cooling medium upon the nose wall.

Several embodiments of the invention are shown in the accompanying drawings in which:

Figure 1 is a fragmentary diagrammatic cross section through the lower end of a blast furnace equipped with the improved tuyère, and also equipped with a monkey constructed in accordance with the present invention;

Fig. 2 is an axial section through a preferred form of improved tuyère;

Fig. 3 is an axial section through a modified form of improved tuyère;

Fig. 4 is an axial section through a still further modified form of improved tuyère;

Fig. 5 is an axial section through a blast furnace monkey constructed in accordance with the present invention; and

Fig. 6 is an end elevation section of the tuyère shown in Fig. 2, taken on the line 6—6;

Similar numerals refer to similar parts throughout the various figures of the drawings.

The lower end of a typical blast furnace is shown in Fig. 1, and the same includes the hearth 5 7, the bosh 8 and a shaft 9 supported upon pillars 10 mounted on the foundation 11. The usual tuyère cooler is shown at 12, and the cinder notch and tapping hole are shown at 13 and 14, respectively.

10 The improved tuyère, indicated generally at 15 in Fig. 1, is mounted in the cooler 12 and the overhang or nose 16 thereof projects into the furnace hearth 7. A blow pipe 17 fits closely within the tuyère and is connected by the tuyère stock 15 18 and the goose neck 19 with the bustle pipe 20, which in turn is connected by a hot blast main to the stoves, not shown.

A cinder cooler, an intermediate or monkey cooler, and a monkey are indicated at 21, 22 and 20 23, respectively, in Fig. 1.

The improved tuyère body 15 includes the outer annular wall 24, an inner annular wall 25 spaced therefrom, each of the same being preferably conically tapered, an outer end or closure or cover

25 wall 26 and the integral inner nose wall or overhang 16. The walls 16, 24, 25 and 26 form an annular cooling jacket cavity or water circulation chamber 27, and a cooling medium, preferably water, may be circulated through the cavity 27 30 by the inlet pipes 28 and the outlet pipes 29.

The outer annular wall 24 is preferably formed at 24a with an increased taper for wedge fitting within the cooling plate 12, and the water or cooling medium inlet and outlet openings or ports 25 30 and 31, respectively, are preferably formed in the outer end wall 26, to which the inlet and outlet pipes 28 and 29 are preferably connected.

The tuyère 15 is preferably cast from genuine copper, which has high heat conductivity, in one piece so that copious circulation of cooling medium through the jacket cavity 27 cannot cause the cooling medium to leak into the furnace hearth. A considerable portion of the metal from which the tuyère is formed is concentrated in the relatively long and massive nose wall or overhang 16 thereof so that a considerable portion of the nose may burn or wear away during furnace operation before the tuyère must be replaced.

50 It has been discovered, in accordance with the present invention, that if the nose wall has a radial thickness R materially greater than one inch and greater than twice the radial thickness of one of the annular walls 24 or 25 and that if the axial length L of the nose wall is one inch or greater, or if it approximates or is greater than the radial thickness R thereof, the desiderata of the invention are attained.

55 By so proportioning the dimensions of the nose wall, the improved tuyère may be used a relatively long time before it must be replaced.

Moreover, the inner surface 34 of the nose wall is cylindrical so that a burning away of a portion of the nose wall does not change the tuyère opening area. Accordingly, the depth of penetration of the blast remains unchanged as the nose burns away.

60 An annular or approximately ring shaped, web-like element or fin 32 preferably projects or extends integrally inwardly from the tuyère body nose wall between and approximately parallel to the spaced annular walls 24 and 25 into the adjacent portion of the jacket cavity 27 for materially increasing the amount of heat given up 75 from or transfer of heat from the nose wall 16

to the cooling medium circulating through the cavity 27.

The tubular air blast passageway 33-34 in the tuyère 15 formed or defined by the inner wall 25 and nose wall 16, provides a nozzle through which the blast is introduced from the blast pipe 17 into the furnace hearth 7.

In certain cases it may be desirable to reduce the weight of the tuyère casting, and this may be accomplished by the modified form of improved tuyère construction indicated generally at 115 in Fig. 3. The tuyère body 115 includes the outer annular wall 124, an inner annular wall 125 spaced therefrom, each of the same being preferably conically tapered, an outer end or closure or cover wall 126 and an integral inner nose wall or overhang 116. The walls 116, 124, 125 and 126 form an annular cooling jacket cavity or water circulation chamber 127, and a cooling medium, preferably water, may be circulated through the cavity 127 by inlet and outlet pipes connected to the water or cooling medium inlet and outlet openings or ports 130 and 131, respectively.

100 The outer annular wall 124 is preferably formed at 124a with an increased taper for wedge fitting within the blast furnace cooler 12, and the tubular air blast passageway 133 in the tuyère 115 is formed or defined by the inner wall 125 and the cylindrical inner surface 134 of the nose wall 116, to provide a nozzle through which the blast is introduced from the blast pipe 17 into the furnace hearth 7. An annular or approximately ring shaped, web-like element or fin 132 preferably projects or extends integrally inwardly from the tuyère body nose wall between and approximately parallel to the spaced annular walls 124 and 125 into the adjacent portion of the jacket cavity 127 for materially increasing the amount of heat given up from or transfer of heat from the nose wall 116 to the cooling medium circulating through the cavity 127.

110 A considerable portion of the metal from which the tuyère is formed is concentrated in the relatively long and massive nose wall 116, which may be provided with an annular channel 116a in order to reduce the weight of the one-piece tuyère casting made preferably from genuine copper which has high heat conductivity. However, in accordance with the present invention, the nose wall 116 extending inward from the cavity 116a 125 has a radial thickness R materially greater than twice the radial thickness of one of the annular walls 124 or 125, and the axial length L of the nose wall is one inch or more and preferably approximates or is greater than the radial thickness 130 R thereof.

120 In some blast furnaces, there is a tendency for the tuyère nose to be burned away only at one portion thereof, which may be either an upper, or a lower, or a side portion. In such cases, the 135 weight of the tuyère casting may be reduced by utilizing the modified form of improved tuyère construction indicated generally at 215 in Fig. 4.

130 The tuyère body 215 includes the outer annular wall 224, an inner annular wall 225 spaced therefrom, each of the same being preferably conically tapered, an outer end or closure or cover wall 226 and an integral inner nose 216. The walls 216, 224, 225 and 226 form an annular cooling jacket cavity or water circulation chamber 227, and a cooling medium, preferably water, may be circulated through the cavity 227 by inlet and outlet pipes connected to the inlet and outlet openings or ports 230 and 231, respectively.

- The outer annular wall 224 is preferably formed at 224a with an increased taper for wedge fitting within the blast furnace cooler 12, and the tubular air blast passageway 233 in the tuyère 215 is formed or defined by the inner wall 225 and the cylindrical inner surface 234 of the nose wall 216, to provide a nozzle through which the blast is introduced from the blast pipe 17 into the furnace hearth 7. 5
- 10 A considerable portion of the metal from which the tuyère is formed is concentrated in the nose 216. In accordance with the present invention, a relatively long and massive solid metal portion 216a of the nose 216 has a radial thickness R 15 materially greater than twice the radial thickness of one of the annular walls 224 or 225, and the axial length L of the nose portion 216a is one inch or more, or approximates or is greater than the radial thickness R thereof. 20
- 25 An annular fin 232 preferably projects or extends integrally inwardly from the heavy nose portion 216a between and approximately parallel to the spaced annular walls 224 and 225 into the adjacent portion of the jacket cavity 227 for 30 materially increasing the amount of heat given up from or transfer of heat from the nose portion 216a to the cooling medium circulating through the cavity 227.
- When the tuyère 215 is installed in the blast furnace, the portion 216a is presented toward that portion of the furnace hearth which causes destruction of the tuyère, so that a burning away of the tuyère nose portion 216a will not require replacement of the tuyère. 35
- 40 An improved cinder notch monkey 23, shown in Figs. 1 and 5, may be constructed in accordance with the present invention by providing an outer annular wall 324, an inner annular wall 325 spaced therefrom, each of the same being preferably conically tapered, an outer end or closure or cover wall 326 and an integral inner nose or overhang 316. The walls 316, 324, 325 and 326 form an annular cooking jacket cavity or water circulation chamber 327 and a cooling medium, preferably water, may be circulated through the cavity 327 by inlet and outlet pipes connected to inlet and outlet openings or ports 330, two of which may be provided in the offset portion 326a of the end wall 326. 45
- 50 The outer annular wall 324 is preferably formed at 324a with an increased taper for wedge fitting within the monkey cooler 22, and the tubular passageway 333 in the monkey 23 is formed by the inner wall 325 and nose 316, to provide for the reception of a cinder notch bott. An annular or approximately ring shaped, web-like element or fin 332 preferably projects or extends integrally inwardly from the nose wall between and approximately parallel to the spaced annular walls 324 and 325 into the adjacent portion of the 55
- 60 jacket cavity 327 for materially increasing the amount of heat given up from or transfer of heat from the nose wall 316 to the cooling medium circulating through the cavity 327. 65
- A considerable portion of the metal from which the monkey is formed, is concentrated in the relatively long and massive nose wall 316, and the monkey is preferably a one-piece genuine copper casting. However, in accordance with the present invention, the monkey nose wall 316 has a radial thickness R materially greater than twice the radial thickness of one of the annular walls 324 or 325, and an axial length L of one inch or more, and preferably approximating or greater than the radial thickness R thereof. 80
- Tuyères or monkeys and the like constructed in accordance with the present invention have relatively long lives and need not be replaced as frequently as the usual tuyères and monkeys ordinarily used. Accordingly, blast furnaces utilizing tuyères and the like constructed in accordance with the present invention can be operated with increased efficiency. 85
- 90
- 95
- I claim:—
1. In an all copper tuyère and the like, a cooling jacket providing a cavity formed by spaced inner and outer annular walls, an outer end wall and an inner nose wall having a heavy solid portion; the solid portion of the nose wall having a radial thickness greater than twice the thickness of one of the annular walls and having an axial length greater than its radial thickness; means for introducing and withdrawing cooling medium to and from the jacket cavity; and a cooling fin spaced between the annular walls projecting into the cavity from the nose wall. 100
- 105
2. In an all-copper tuyère and the like, a cooling jacket providing a cavity formed by spaced inner and outer tubular walls, an outer end wall and an inner nose wall having a heavy, solid, copper portion integral with the tubular walls; the solid portion of the nose wall having a thickness greater than twice the thickness of one of the tubular walls and having an axial length greater than its thickness; and means for introducing and withdrawing cooling medium to and from the jacket cavity. 115
- 120
3. In an all-copper tuyère and the like, a cooling jacket providing a cavity formed by spaced inner and outer tubular walls, an outer end wall, and an inner nose wall having a heavy, solid, copper portion integral with the tubular walls; any dimension of the solid nose wall being greater than twice the thickness of one of the tubular walls adjacent to the solid nose wall, and materially greater than one inch; and means for introducing and withdrawing cooling medium to and from the jacket cavity. 125
